(No Model.)

F. W. OSTROM.

CLAMP OPERATING MECHANISM FOR BUTTON HOLE SEWING MACHINES.

No. 398,344.

Patented Feb. 19, 1889.

UNITED STATES PATENT OFFICE.

FREELAND W. OSTROM, OF BRIDGEPORT, CONNECTICUT, ASSIGNOR TO THE WHEELER & WILSON MANUFACTURING COMPANY, OF SAME PLACE.

CLAMP-OPERATING MECHANISM FOR BUTTON-HOLE SEWING-MACHINES.

SPECIFICATION forming part of Letters Patent No. 398,344, dated February 19, 1889.

Application filed May 20, 1886. Serial No. 202,733. (No model.)

To all whom it may concern:

Be it known that I, FREELAND W. OSTROM, of Bridgeport, county of Fairfield, and State of Connecticut, have invented an Improvement 5 in Cloth-Clamping Mechanism for Button-Hole-Stitching Machines, of which the following description, in connection with the accompanying drawings, is a specification, like letters on the drawings representing like parts.

10 In machines for stitching button-holes it is customary to hold the material between the members of a clamp, the upper member being raised whenever it is desired to unclamp the material by a movement produced by the hand 15 of the operator.

In stitching button-holes rapidly by machinery the operator has frequently to clamp and unclamp the material, and usually has to trim the threads from the holes, mark the 20 goods for the next button-hole, and cut the same, and the operator to perform all this work properly has very considerable to do, and the time consumed by the operator in laying down and picking up her scissors and 25 other tools, which are almost constantly in use, in order to operate the clamp, is very considerable, and results in quite a loss in the aggregate. To obviate this consumption of 30 time and enable the operator to have the free use of both her hands in preparing, gaging, cutting, and trimming, or otherwise manipulating her work, I have provided means whereby the clamp may be operated from the under side of the machine table or bench by or 35 through some member of the body other than the hands whenever it is necessary to change the position of the material in the clamp.

In this present embodiment of my invention I have shown the clamp as actuated by 40 levers under the control, one of the foot and the other of the knee, the said levers being joined to one member of the clamp by a connection which in practice will preferably be a chain; but it may be a cord or rod suitably 45 jointed, the foot being preferable when the power-driven shaft is controlled by usual stop-motions and the knee-lever for foot-power, the left foot with usual power-driven machines being free for such purpose; but when the 50 machine is driven by foot-power, as it may

be, the knee is the most available member to use for actuating the clamp.

My invention consists, essentially, in a clamp to hold the material to be stitched, combined with a connector by which to operate it, the 55 said connector being extended below the table or bench upon which the machine is supported, the said connector being attached to a lever or other usual device, which may be readily acted upon by the foot or leg. 60

Figure 1 in side elevation represents my improvements connected to a sewing-machine on a table; Fig. 2, a detail showing part of the table and the clamp in side elevation, the connector below the knee-lever shaft being omitted; and Fig. 3, a top or plan view, on a smaller 65 scale, of the clamp resting upon the cloth-plate of the machine and part of the table-top.

The sewing-machine herein shown and marked A and the cloth-clamp-feeding mechanism B are and may be of usual construction. 70

The machine and cloth-clamp-feeding mechanism herein shown are substantially as described in United States Patent No. 303,453, 75 and known as the "Wheeler & Wilson automatic button-hole-stitching machine."

The machine is shown as mounted upon a table, C, of usual construction, the said table having, as herein shown, a rod, C', to support the foot-treadle C'; but the said treadle may be supported in any usual manner. 80

I have also mounted below the table in suitable bearings a shaft, D, having attached to it a knee-lever, D', the opposite end of the 85 said shaft having an arm, D². As herein shown, I have also attached to the said shaft a second arm, D³, having a pin, D⁴, which, acting against one of the said bearings or a stationary part of the table, serves as a back-stop to prevent unduly straining the upper member, G', of the cloth-clamp. 90

The lower member, G, of the cloth-clamp, having, as usual, an opening for the passage of the needle in stitching the material held between the said lower member and the upper member, G', has erected upon it a block, a, to which is hinged or pivoted at a' the upper member, G', of the clamp, it having an opening for the passage of the needle and

also having connected to it below and about said opening a cloth presser-foot, H, substantially such as shown in the patent referred to. The lower member at its forward end, nearest the operator, has its edge passed under a button, a^3 , which prevents the twisting or straining of the said member G when the clamp is being operated from below the table. The lower member, G, of the clamp has a stud, 10 a^4 , which is extended through a hole in the upper member, where it receives upon it a spring, a^5 , and thereafter a nut, a^6 , by which to regulate the pressure of the said spring, the spring acting to force the upper member down upon the material laid between it and the lower member to be stitched. The upper member, G', has, as herein shown, 15 an ear or post, b, to which is jointed an arm, G³, the said arm being of greater or less length to enable it to be properly and conveniently joined to the connector E, which, extended below the table, is to be employed to operate the clamp whenever it is necessary to change the position of the material therein. By hinging the arm G³, as shown, it is free to turn upon its pivot b^4 when the machine is tipped over upon its side upon the table C, which is frequently done in use; but, if desired, this arm may be connected rigidly to the main part G' 20 of the clamp and the top of the table be cut out for the reception of the end of the arm G³ when the machine is tipped over. When the arm G³ is jointed, as shown, the block a at the rear end of the portion G' of the clamp 25 acts as a fulcrum for it. The jointing of the arm G³ is a matter of very considerable convenience in packing machines for shipment. The connector E herein shown, and which I prefer to use, is represented as a chain. 30 This connector at a point below the table is shown as jointed not only to one end of the arm D² of the shaft D to be actuated by the knee, but also to the treadle or foot-piece C², so that by the pressure of the foot or some 35 part of the leg the connector may be moved to effect such a movement of the cloth-clamp as will enable the operator to move the work

or change its position in the clamp, this being done without the assistance of the hand of the operator.

50 The connector shown, being flexible, may be run in any desired direction and be made to run against rollers or sheaves whenever it touches any part between the clamp and treadle.

55

I claim—

1. The combination, with the stitch-forming mechanism, of a button-hole sewing-machine and a cloth-holding clamp having reciprocating movements in opposite directions parallel to the length of the button-hole while the said button-hole is being stitched, an arm, G³, projecting from the cloth-holding clamp, a lever constructed to be operated by an operator's knee or foot, and a connector interposed between the arm and lever, substantially as described.

60 2. The combination, with the stitch-forming mechanism, of a button-hole sewing-machine and a cloth-holding clamp having reciprocating movements in opposite directions parallel to the length of the button-hole while the said button-hole is being stitched, an arm, G³, pivoted to the cloth-holding clamp, a lever constructed to be operated by an operator's knee 65 or foot, and a connector interposed between the arm and lever, substantially as described.

70 3. In a button-hole sewing-machine, the bed-plate, combined with the cloth-holding clamp and a button for securing it thereto, the arm G³, hinged to the upper member of the clamp, a knee or foot lever arranged below the table, and a flexible connector uniting the arm and lever, and at the same time permitting of the tipping of the sewing-machine, substantially 75 as shown and described.

80 In testimony whereof I have signed my name to this specification in the presence of two subscribing witnesses.

FREELAND W. OSTROM.
